UNITED STATES PATENT OFFICE.

ANDRÁS HAJAS HAJASOK, IMRE HAJAS HAJASOK, AND JÓZSEF HAJAS HAJASOK, OF
GARY, WEST VIRGINIA.

WHEEL-ANCHORING BLOCK CONSTRUCTION.

1.174.410.

Specification of Letters Patent.

Patented Mar. 7, 1916.

Application filed November 1, 1915. Serial No. 59,111.

To all whom it may concern:

Be it known that we, ANDRÁS HAJAS HAJASOK, IMRE HAJAS HAJASOK, and JÓZSEF HAJAS HAJASOK, subjects of the King of Hungary, residing at Gary, in the county of McDowell and State of West Virginia, have invented certain new and useful Improvements in Wheel-Anchoring Block Construction, of which the following is a specification.

10

This invention relates to certain new and useful improvements in wheel anchoring block construction.

15

The primary object of the invention is the provision of an anchoring means for the wheels of vehicles such as gun carriages and ammunition wagons and whereby the same may be securely blocked and anchored at any desirable location.

20

A further object of the device is to provide oppositely positionable ground-engaging anchoring means adjustably positioned at opposite sides of a wheel and readily removable therefrom.

25

A still further object of the invention is to provide a readily removable adjustable wheel anchoring means adapted for maintaining such vehicles as gun carriages in their desired fixed positions during the use 30 of the vehicle such as firing of a gun or cannon mounted upon the vehicle.

35

With these general objects in view and others that will appear as the nature of the invention is better understood, the same 40 consists in the novel combination and arrangement of parts hereinafter more fully described, illustrated in the accompanying drawings, and forming a part of the appended claims.

45

In the drawings forming a part of this application and in which like-designating characters refer to corresponding parts throughout the several views:—Figure 1 is a side elevation of a rear portion of the vehicle provided with the present device in its operative position. Fig. 2 is a horizontal sectional view taken upon line II—II of Fig. 1, and Fig. 3 is an end elevational view of one of the chock blocks of the device.

50

While the present invention is serviceable in connection with the wheels of any vehicle, the same is herein illustrated as operatively attached to one of the rear wheels 10 of

a wagon 11, the surface of the ground being illustrated at 12 upon which the wagon is 55 standing.

Identical wedge or chock blocks 13 are provided having a base 14 adapted to be positioned upon the ground and provided with oblique calks 15 for projecting thereinto, 60 the inclination of the said calks being toward the upright or rear side 16 of the block 13.

The said upright and base sides 16 and 14 respectively of the block are arranged perpendicular to each other, while the third side 17 thereof which corresponds to the hypotenuse of the triangle is of arcuate form corresponding to the circumference of the wheel 10 and being U-shaped in cross 70 section forming a central channel 18 adapted for the reception of the wheel. With the blocks 13 so positioned upon the ground in engagement with the opposite sides of the wheels as illustrated in Fig. 1, hooks 19 are 75 engaged within the loops 20 at the inner ends of the blocks, while a turn buckle 21 connects the said hook and may be employed for drawing the blocks together, the calks 15 being outwardly inclined for allowing 80 the blocks to move in the said direction. A double turn-buckle connecting means 22 connects oppositely arranged rings 23' at the upper inner side of the blocks 16 for drawing and retaining the tops of the blocks 85 together. Chains 23 are adapted to be hooked around two of the upper spokes 24 of the wheel and to be attached to similar turn buckle means 25 which have their lower end hooks 26 removably attached to 90 staples 27 at the angular portion 28 of the said block.

The blocks 13 are positioned in engagement with the opposite sides of the wheel 10 as illustrated in Fig. 1 of the drawings 95 and in which positions the calks 15 of the said blocks are securely embedded in the ground, while the turn buckle means 21, 22 and 25 removably retain the said blocks in their holding positions engaging the wheel. 100 The vehicle is thus prevented from traveling by locking the wheel 10 against rotation, but when desired to employ the vehicle 11 for purposes of travel, the turn buckles may be readily detached and the blocks 16 removed thus releasing the wheel from its ob- 105

structions and allowing the same to readily revolve.

While the form of the invention herein shown and described is what is believed to be the preferred embodiment thereof, it is nevertheless to be understood that minor changes may be made therein without departing from the spirit and scope of the invention as claimed.

10 What we claim as new is:—

1. A wheel locking device comprising oppositely - positionable substantially triangular blocks having their inner faces U-shaped in cross section, outwardly and downwardly inclined calks carried by the lower faces of the bases of the said blocks, ring members at the three corners of the said blocks, and removable turn buckle attaching means operatively attached to the said ring members.

15 2. A device of the class described com-

prising in combination with a wheel, substantially triangular shaped blocks oppositely arranged and having their inner sides curved and substantially U-shaped in cross section engaging over the edges of the said wheel, rings mounted upon the corners of the said blocks, connecting turn - buckle means between the upper and inner pairs of said rings, adjustable turn buckle means connecting the outer corner rings with the 25 upwardly positioned blocks of the said wheel, and downwardly and outwardly projecting calks upon the said posts of the said blocks.

30 In testimony whereof we affix our signatures.
